UNITED STATES PATENT OFFICE.

JOHN F. O'CONNOR, OF CHICAGO, ILLINOIS, ASSIGNOR TO WILLIAM H. MINER, OF CHAZY, NEW YORK.

DRAFT-RIGGING FOR RAILWAY-CARS.

1,302,073.

Specification of Letters Patent. Patented Apr. 29, 1919.

Application filed March 30, 1917. Serial No. 158,496.

To all whom it may concern:

Be it known that I, JOHN F. O'CONNOR, a citizen of the United States, residing at Chicago, in the county of Cook and State of Illinois, have invented a certain new and useful Improvement in Draft-Rigging for Railway-Cars, of which the following is a full, clear, concise, and exact description, reference being had to the accompanying drawings, forming part of this specification.

My invention relates to improvements in draft rigging for railway cars.

The object of my invention is to provide an efficient and simple friction spring draft rigging.

In the drawings forming a part of this specification, Figure 1 is a horizontal section of a draft rigging embodying my invention. Fig. 2 is a cross section taken on line 2—2 of Fig. 1. Fig. 3 is a perspective view of one of the friction plates. Fig. 4 is a side elevation of the front follower.

Referring to the drawings, the numerals 10—10 indicate draft members, as, for instance, draft sills, being the parts of the car frame to which the draft rigging is applied, 11—11 the front stop members, and 12—12 the rear stop members, all suitably secured to the draft members, as, for instance, by the rivets 13—13. A draw-bar is indicated at 15, and a yoke at 16, appropriately secured to the draw-bar, as, for instance, by the rivets 17. Within the yoke is the draft gear 18.

The draft gear comprises a shell 19 open at its forward end 20 and closed at its rear end by the preferably integral plate or rear follower 21. The forward end 20 is provided with a rearwardly converging throat 121 forming the friction faces 22—22 upon the shell. Each of these friction faces is engaged by a friction shoe 23, the said shoes each having a friction face 24 engaging the adjacent friction face of the shell, and a plurality, as, for instance, two longitudinally arranged ribs 25—25 upon their inner faces, the same being spaced apart to receive the ends of the friction plates 26 which are transversely arranged between the friction shoes. The friction plates comprise a series of alternately arranged interlaced U-shaped members 27—27, each at its closed end 28 passing about a pin 29 passed through suitable perforations 30—30 in the flanges 25 upon the friction shoes. An in-

termediate follower 31 provided with a forwardly extended boss 32 engages the rear end of the transversely arranged friction plates, and at the forward end the said friction plates are engaged by the front follower 33 which is provided with a convexity or boss 34 upon its inner face. Rearwardly of the intermediate follower are mounted the springs 35 which are seated within the shell between its rear end and the intermediate follower. The front follower 33 is provided with upper and lower rearwardly extended arms 36—36 suitably spaced apart to pass, respectively, above and below transversely arranged spring plates. The draft gear is suitably supported by the carrier plate 37 which is secured to the draft members, as, for instance, by the bolts 38—38.

In rearward movement of the draw-bar, the shell is held against rearward longitudinal movement by the rear stop members. The transversely arranged friction plates are pressed into engagement with each other between the front follower 33 and the intermediate follower 32. The intermediate follower is resisted in its rearward movement by the springs 35. As the front follower travels rearwardly, the transverse friction plates yield slightly until the follower engages the front ends 39 of the friction shoes, and as the same move rearwardly in the throat of the shell they are in frictional contact with the friction face of the shell and at the same time the arms of the friction plates slide upon each other as the friction shoes travel rearwardly and toward each other. Meanwhile the friction elements as a whole are resisted by the springs 35. Upon the release of the draw-bar's pressure the said springs 35 force the friction parts to their normal position.

On forward movement of the draw-bar, the shell is drawn forwardly by the yoke, the gear being stopped at its forward end through the engagement of the front follower 33 against the front stop, and the action of the internal parts of the shell upon its forward movement will be similar to their action in rearward movement, as just described, as will be readily understood.

I claim:

1. In a shock absorbing mechanism for railway cars, the combination with draft members, stops associated therewith, a draw bar, a shell, means for operatively connect-

- ing the shell to the draw bar, and a follower, of spring means within the shell, said shell having an inwardly tapered throat at one end, friction shoes within said throat and disposed opposite each other and extending lengthwise of the throat, friction plates extending transversely between said shoes and held in engagement with each other by said spring means, said friction plates being adapted to slide upon each other on movement of the friction shoes, the ends of some of said friction plates on one side being attached to one shoe and the ends of other friction plates on the other side being attached to the other shoe.
2. In a shock absorbing mechanism, in combination: a shell, springs and friction elements within the shell, the shell being provided with inclined friction faces, shoes to engage said faces, and friction plates transversely arranged between said shoes, the said friction plates comprising interlaced U-shaped members secured to the shoes.
3. In a shock absorbing mechanism, in combination: a shell; friction elements and springs within the shell, the shell having inclined friction faces, the friction elements comprising shoes engaging said friction faces and having interlaced U-shaped friction plates, the said plates being secured at their closed ends to said friction shoes, the spring being adapted to resist the movement of the friction elements.
4. In a shock absorbing mechanism, in combination: a friction shell, friction elements and spring means within the shell; end and intermediate followers; said shell being provided with inclined friction faces, said friction elements including friction shoes engaging and extending lengthwise of said inclined friction faces, and transversely arranged friction plates between said shoes, each shoe having a plurality of friction plates attached thereto, said spring means engaging said intermediate follower and being adapted to compress the friction plates between said intermediate follower and the end follower.
5. In a shock absorbing mechanism, in combination: a shell; friction elements and springs within the shell; front and intermediate followers; the shell being provided with an inclined friction face, the friction elements including shoes engaging said faces and transversely arranged friction plates associated with said shoes and mounted between said followers, the springs engaging one of said followers and being adapted to compress the friction plates between said

follower and the other follower, said friction plates being U-shaped, alternately arranged, interlaced members.

6. In a shock absorbing mechanism, in combination: a shell; friction elements and springs within the shell; front and intermediate followers; the shell being provided with an inclined friction face, the friction elements including shoes engaging said faces and transversely arranged friction plates associated with said shoes and mounted between said followers, the springs engaging one of said followers and being adapted to compress the friction plates between said follower and the other follower, said friction plates being U-shaped, alternately arranged, interlaced members, the said plates being secured at their closed ends to the friction shoes.

7. In a shock absorbing mechanism, in combination: a friction shell, friction elements and spring means within the shell; said shell being provided with inclined friction faces, said friction elements including friction shoes engaging said friction faces and interlaced friction plates, said spring means pressing against said plates and the friction plates sliding upon each other upon movement of said shoes lengthwise of the inclined friction faces, each shoe having a plurality of friction plates secured thereto.

8. In a shock absorbing mechanism, a shell, friction elements and springs within the shell, the shell having inclined friction faces, the friction elements including shoes engaging said faces and friction plates, said friction plates comprising alternately arranged interlaced U-shaped members, said members being pinned to the shoes at their closed ends, the spring being adapted to hold said friction plates in engagement with each other.

9. In a shock absorbing mechanism, a shell, friction elements and springs within the shell, the shell having inclined friction faces, the friction elements including shoes engaging said faces and friction plates, said friction plates comprising alternately arranged interlaced U-shaped members, said members being pinned to the shoes at their closed ends, the spring being adapted to hold said friction plates in engagement with each other, the said plates sliding each upon another on approaching or separating movement of the friction shoes.

In witness that I claim the foregoing I have hereunto subscribed my name this 20th day of Mar., 1917.

JOHN F. O'CONNOR.
